UNITED STATES PATENT OFFICE.

SAMUEL L. WHITRIGHT, OF WATERBURY, CONNECTICUT.

DENTAL COTTON-HOLDER.

1,078,230.

Specification of Letters Patent.

Patented Nov. 11, 1913.

Application filed September 5, 1913. Serial No. 788,207.

To all whom it may concern:

Be it known that I, SAMUEL L. WHITRIGHT, a citizen of the United States, and a resident of Waterbury, in the county of 5 New Haven and State of Connecticut, have invented certain new and useful Improvements in Dental Cotton-Holders, which improvements are fully set forth in the following specification.

10 This invention relates to improvements in devices of that class available for the accessible storage of a supply of absorbent, medicated, or other cotton, such devices being more particularly intended for dentists' 15 use, and being appropriately designated dental-cotton holders.

The object of this invention is to provide 20 a dental-cotton holder which shall be simple and comparatively inexpensive as regards its construction; durable, efficient and reliable in practical service; which shall embody novel features of construction whereby are markedly facilitated both the 25 operation of gaining access to the interior of the holder, proper, as for the charging thereof, from time to time, with fresh supplies 30 of cotton, and the adjusting thereto and displacement therefrom, also as occasion may make needful, of the waste-cotton receptacle thereof; and which shall possess 35 certain well-defined advantages over prior analogous structures.

The invention consists in the combinations, details and parts whereby, together 40 with the novel disposition and relative arrangement of said parts, the attainment of the foregoing object is rendered practicable, all of which will be hereinafter more specifically referred to and set forth in the appended claims.

In the accompanying drawing, wherein 45 the invention is clearly illustrated, and similar reference-characters denote like parts throughout the respective views,—Figure 1 is a plan view of a dental-cotton holder embodying my said improvements, a fragment of the perforated mantle thereof being broken away. Fig. 2 is a side elevation of same, the waste-receptacle saddle 50 thereof being shown in central, vertical section, as along the broken line $x-x$ of Fig. 1, the perforated mantle and interior dome of the holder, being each partially broken away. Fig. 3 is a view showing in perspective and detached the saddle aforenamed 55

in conjunction with the frictional keeper which I purpose making use of.

Having reference to the accompanying drawing, 2 denotes the interior dome of the device, provided with a base-plate 2', said dome having an opening 2'' at its top. Within the dome 2 there is disposed a frictional keeper, the same consisting, in this instance, of a flat bottom-member 3, merged at its opposite end-portions into upstanding, 65 somewhat upwardly converging, opposite legs 3'', 3'', each having a terminal at its upper extremity turned oppositely to the opposite leg, and said keeper being positioned so that the space between its legs 3'', 3'' registers vertically with the opening 2'' thereover.

4 denotes a dome-like mantle, which overhangs and generally houses the dome 2, said mantle and said dome being so at variance 75 in cross-sectional contour as to provide between them a chamber 4', for the reception from time to time, and storage of supplies of fresh cotton, and said chamber being co-extensive circumferentially with the holder, 80 proper. The dome 2 is provided, by preference, with a circumferential ledge 4'', at the lower portion thereof, and on which ledge rests the mantle 4, when in position for service. Said mantle is provided with a 85 plurality of perforations 5, preferably arranged in series circumferentially thereof, and the purpose of said perforations will be hereinafter explained.

The mantle 4 is surmounted by a saddle 5' 90 for the reception and seating of a waste-cotton receptacle 5''. It is contemplated and preferred that the saddle aforenamed shall be capable of not only affording a seat for the receptacle 5'', but of exerting a frictional holding force thereon, when the latter is in position for service; and to this end saddle 5' is provided marginally with a plurality of upstanding clip-members 6, each adapted to elastically impinge, at its 100 upper portion, against the adjacent wall of the receptacle 5'', the latter being inserted downwardly endwise between such clip-members.

Any appropriate fastening medium may 105 be availed of for securing the saddle 5 on the mantle 4, though, as here shown, I have provided a central tie-stem 6', having a head 6'', which tie-stem extends downwardly through the saddle 5, by way of a suitable 110

opening 7 formed centrally therein, thence downwardly through the dome 2, by way of the opening 2" formed therein at its top, and terminates at a point suitably distant 5 downwardly from the top of the dome 2 to permit the same to crowd, end-on, between the legs 3", 3", of the keeper aforesigned, whereby a frictional holding force is exerted thereon by the latter. Also, in this instance, 10 the shank of said tie-stem is suitably threaded to receive a fastening nut 7', the central portion of the saddle 5' and of the crown of the mantle 4 lying, one upon the other, between the head 6" of said tie-stem, and the 15 fastening nut aforesigned, said saddle and said mantle being, accordingly, duly locked together, upon said fastening nut being adequately turned homeward, all as will be readily understood.

20 As to the practical operation of my improved cotton holder, it will be understood that mantle 4 may be displaced from, and replaced on, the dome 2, by exerting lengthwise on the stem 6' a mere pulling force, in 25 the former instance, and a mere pushing force in the latter instance, these opposite forces being readily applied to said stem, although indirectly in this instance, by grasping the dome 2, with one hand as at 30 its circumferential ledge 4', and grasping, say, the saddle 5' with the other hand. Again, when mantle 4 is displaced from the dome 2, a suitable supply of fresh cotton may be lodged upon the latter, the mantle 4 35 being then replaced upon said dome; whereupon the cotton will occupy the chamber 4', intermediate of, and formed by, said mantle and said dome, respectively, access to said cotton, in comparatively small quantities, as 40 required for service, being then had by way of any of the perforations 5. The discarding of the cotton, in said comparatively small quantities, and after being soiled in use, the user effects by inserting the same 45 into the receptacle 5", by way of the customary cross-slitted top thereof, this receptacle being commonly formed from paper.

The positioning of the receptacle 5" on the saddle 5', and its removal therefrom, are 50 effected in substantially the same manner as are effected the positioning of the mantle 4 on, and its removal from, the dome 2, as hereinbefore explained.

The general parts of my improved cotton holder, aside from the receptacle 5", may be 55

formed from any suitable material, preference being given to thin-sheet-metal.

It will be seen that my improved dental-cotton holder is well adapted for the purposes for which it is intended, and further 60 that the same may be modified to a considerable extent, particularly as regards the specific character of the keeper made use of for frictionally grasping the stem 6', the specific element or elements whereby the saddle 65 5' is rendered capable of exerting a frictional holding force on the receptacle 5", and various minor details of the general construction, without departing from the scope of the claims hereto appended. 70

I claim:

1. A dental-cotton holder comprising an interior dome; a perforated mantle overhanging and substantially housing said dome; and means whereby said mantle and 75 said dome are frictionally held together.

2. A dental-cotton holder comprising an interior dome; a perforated mantle overhanging and substantially housing said dome, and having a stem freely depending 80 therein; and a keeper, the latter situated within said dome, and adapted to engage and frictionally exert a holding force on said stem.

3. A dental-cotton holder comprising an 85 interior dome; a perforated mantle overhanging and substantially housing said dome, said mantle surmounted by a waste-receptacle saddle, and having a stem tying said saddle thereto, and freely depending 90 within the dome aforesigned; and a keeper, the latter situated within said dome and adapted to engage and frictionally exert a holding force on said stem.

4. A dental-cotton holder comprising an 95 interior dome; a perforated mantle overhanging and substantially housing said dome, said mantle surmounted by a waste-receptacle saddle affording a plurality of up-standing clip-members, and having a stem 100 tying said saddle thereto, and freely depending within the dome aforesigned; and a keeper, the latter situated within said dome and adapted to engage and frictionally exert a holding force on said stem.

SAMUEL L. WHITRIGHT.
